(57) **CLAIM**

The ornamental design for a loudspeaker, as shown and described.

DESCRIPTION

FIG. 1 is a perspective front view of a loudspeaker showing my new and ornamental design,

FIG. 2 is a front view thereof,

FIG. 3 is a rear view thereof,

FIG. 4 is a side view thereof,

FIG. 5 is an opposite view thereof,

FIG. 6 is a top view thereof; and,

FIG. 7 is a bottom view thereof.

The broken lines shown are included for the purpose of illustrating portions of the loudspeaker that form no part of the claim.

The speaker grill pattern is understood to repeat throughout the front surface upon which it is applied.
